(57) CLAIM

The ornamental design for a securing base for a drum, as shown and described.

DESCRIPTION

FIG. 1 is a perspective view of a securing base for a drum showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is another perspective view, wherein the broken lines illustrate an alternative environment only and form no part of the claimed design; and,

FIG. 9 is a perspective view thereof in a reduced size, embodying the utilization of my new design, the drum portion depicted by means of broken lines being for illustrative purposes only and forming no part of the claimed design.
